UNITED STATES PATENT OFFICE.

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS.

OIL-BURNING FURNACE AND THERMOSTATIC CONTROL THEREFOR.

Application filed February 8, 1926. Serial No. 86,696.

My invention relates to thermostatic control means for a furnace and has for a particular purpose the provision of means for thermostatically controlling the feed of liquid or gaseous fuel to a burner employed in a hot air heating system. One object of my invention is to provide thermostatic control means for such a burner which shall be responsive to the temperature of a hot air heating system. Another object is to provide thermostatic control means of the type described which shall also be responsive to temperature conditions in the furnace itself. Other objects will appear from time to time in the course of the specification and claims.

I illustrate my invention more or less diagrammatically in the accompanying drawings, wherein—

20 Figure 1 is a vertical section; and

Figure 2 is a detail, on an enlarged scale.

A generally indicates any suitable furnace comprising, for example, a base section A¹, intermediate sections or segments 25 A² A³ and an upper segment A⁴ provided with the flue A⁵.

B is a surrounding air housing or jacket provided with a plurality of hot air passages B¹ and a return cold air passage B².

30 C diagrammatically illustrates any suitable form of liquid or gaseous fuel burner, the details of which are not described and shown and form no part of the present invention. C¹ is a fuel supply pipe communicating with a float chamber C². C³ is a float mounted in such chamber, the float arm C⁴ being pivoted intermediate its ends as at C⁵. Its opposite end is secured, as at C⁶, to the valve stem C⁷, the tapered end

35 C⁸ of which is adapted to control the inner end of the supply pipe C¹.

D is a fuel line extending from the float chamber C² to the oil burner C. Its outer end communicates with the passage D¹ through 40 the tapered valve seat D² in the bottom of the float chamber C². Aligned with said valve seat D² is the needle valve stem D³ with its tapered end D⁴, which is normally

thrust into closing position, for example, by the coil compression spring D⁵. The upper end of the valve stem D³ passes upwardly through the lower wall of the cold air passage B² and is secured to the thermostatic strip E which is mounted in any suitable fashion within the passage B², for example, upon the securing member or standard E¹. The thermostatic member is preferably mounted sufficiently close to the inner end of the passage B² to be in line with the furnace A and to be subjected to direct radiation of heat therefrom.

It will be realized that whereas I have illustrated a practical and operative device, that nevertheless many changes might be made in the size, shape, number and disposition of parts without departing from the spirit of my invention. I therefore wish my description and drawings to be taken as in a broad sense illustrative or diagrammatic rather than as limiting me to my particular description and showing. In particular, my invention may be applied to a gas burner as well as to an oil burner. The use and operation of my invention are as follows:

I employ any desired type of furnace 75 within any suitable air jacket or housing, it being understood that the furnace heats the air within such housing, that the heated air passes upwardly through any suitable passages or conduits to the rooms to be 80 heated, and that the general cold air return passage B² delivers to the bottom of the air jacket B the cold air from the house. In general practice this volume of cold air so returned is a fair average of the minimum 85 temperatures or the return air temperatures of the various rooms of the house.

I employ any desired form of burner in which a liquid or gaseous fuel is burned, and I control the flame, and thus the heating 90 capacity of the unit, by controlling the inflowing volume of fuel in response to changes in temperature of the returning volume of cold air. I effect this result by positioning a relatively delicate thermostatic element, for example, a thermostatic 95

loop or strip, in the return air passage. In the particular form herein shown, this strip is secured to and positively controls the valve stem D³ and thus the valve passage D¹.

- 5 It may happen, particularly when a number of windows have been left open, that the temperature of the return air may be unduly cold, even though the burner is burning with a very high flame. In order 10 to prevent overheating and fuel waste under such circumstances, I so position the thermostat that it is exposed to the radiant heat of the furnace or is sufficiently near the furnace to react to a predetermined furnace 15 temperature, even though the temperature of the inflowing cold air is so low as to tend normally to permit a large fuel flow. Thus the fuel valve is partially or entirely closed, when the temperature of the return 20 air passes a predetermined maximum, and the valve is also closed, regardless of such air temperature, when the furnace itself is heated beyond a predetermined maximum.

I claim:

- 25 1. In combination with a heating system comprising a furnace, a fuel burner therein, a fuel line thereto, a control valve in said fuel line, an air enclosing housing about said furnace, hot air outlet means extending therefrom and a return cold air duct thereto, a thermostatic control means for said fuel line comprising in part a thermostatic element responsive to the temperature of the air of the return duct.
- 30 35 2. In combination with a heating system comprising a furnace, a fuel burner therein, a fuel line thereto, a control valve in said fuel line, an air enclosing housing about said furnace, hot air outlet means extending therefrom and a return cold air duct thereto, a thermostatic control means for said fuel line comprising in part a thermostatic element responsive to the temperature of the air of the return duct, and so positioned as 40 45 to be responsive also to the heat of the furnace.

3. In combination with a heating system comprising a furnace, a fuel burner therein, a fuel line thereto, a control valve in said fuel line, an air enclosing housing about said furnace, hot air outlet means extending therefrom and a return cold air duct thereto, a thermostatic control means for said fuel line comprising in part a thermostatic element responsive to the temperature of the air of the return duct, and so positioned as 50 55 to be responsive also to radiation of heat from the furnace.

4. In combination with a heating system comprising a furnace, a fuel burner therein, a fuel line thereto, a control valve in said fuel line, an air enclosing housing about said furnace, hot air outlet means extending therefrom and a return cold air duct there- 60 65 to, a thermostatic control means for said

fuel line comprising in part a thermostatic element positioned within the said return duct.

5. In combination with a heating system comprising a furnace, a fuel burner therein, a fuel line thereto, a control valve in said fuel line, an air enclosing housing about said furnace, hot air outlet means extending therefrom and a return cold air duct thereto, a thermostatic control means for said fuel line comprising in part a thermostatic element positioned within the said return duct at such a point as to be responsive to a predetermined excess temperature of the furnace.

6. In combination with a heating system comprising a furnace, a fuel burner therein, a fuel line thereto, a control valve in said fuel line, an air enclosing housing about said furnace, hot air outlet means extending therefrom and a return cold air duct thereto, a thermostatic control means for said fuel line comprising in part a thermostatic element positioned within the said return duct adjacent the point of discharge of said duct into the furnace enclosing housing.

7. In combination with a heating system comprising a furnace, a fuel burner therein, a fuel line thereto, a control valve in said fuel line, an air enclosing housing about said furnace, hot air outlet means extending therefrom and a return cold air duct thereto, a thermostatic control means for said fuel line comprising in part a thermostatic leaf positioned within said return duct, a valve seat in said fuel line, and a valve member opposed thereto and a connection between said valve member and said leaf.

8. In combination with a heating system comprising a furnace, a fuel burner therein, a fuel line thereto, a control valve in said fuel line, an air enclosing housing about said furnace, hot air outlet means extending therefrom and a return cold air duct thereto, a thermostatic control means for said fuel line comprising in part a thermostatic leaf positioned within said return duct, a valve seat in said fuel line, and a valve member opposed thereto and a connection between said valve member and said leaf, such thermostatic leaf being so positioned as to be responsive also to radiation of heat from the furnace.

9. In combination with a heating system, comprising a furnace, a fuel burner therein, a fuel line thereto, a control means in said fuel line, an air enclosing housing about said furnace, hot air outlet means extending therefrom and a return cold air inlet means thereto, and thermostatic control means for said fuel line comprising in part a thermostatic element responsive to the temperature of the returned cold air.

10. In combination with a heating system, comprising a furnace, a fuel burner therein,

a fuel line thereto, a control means in said fuel line, an air enclosing housing about said furnace, hot air outlet means extending therefrom and a return cold air inlet means thereto, and thermostatic control means for said fuel line comprising in part a thermostatic element responsive to the temperature of the returned cold air, and so positioned as to be responsive also to a predetermined excess temperature of the furnace. ¹⁰

Signed at Chicago, county of Cook and State of Illinois, this 5th day of February, 1926.

JAMES L. BREESE, JR.
